(57) CLAIM

The ornamental design for a feminine hygiene pad, as shown and described.

DESCRIPTION

FIG. 1 is a front elevational view of a feminine hygiene pad showing my new design;

FIG. 2 is another front elevational view of a feminine hygiene pad.

FIG. 3 is a top plan view thereof;

FIG. 4 is a side view thereof;

FIG. 5 is an end view thereof; and,

FIG. 6 is a bottom view thereof.

The broken line showing of a feminine hygiene pad is included for the purpose of illustrating environmental structure and forms no part of the claimed design.

The applied stipple shading on the wing perimeter represents a color contrast.

The dash dot line represents the boundary of the claim design.
